CLAIM

The ornamental design for a vehicle rock grille, as shown and described.

DESCRIPTION

FIG. 1 depicts a front, top, left perspective view of a vehicle rock grille showing our new design.

FIG. 2 depicts a front, bottom, right view thereof.

FIG. 3 depicts a front view thereof.

FIG. 4 depicts a perspective of the back side thereof.

FIG. 5 depicts a left side view thereof.

FIG. 6 depicts a right side view thereof.

FIG. 7 depicts a top view thereof; and,

FIG. 8 depicts a bottom view thereof.

The ghosted or low contrasted portions of the vehicle rock grille illustrate portions that form no part of the claimed design. The dash lines depict boundaries of the claimed design.

1 Claim, 7 Drawing Sheets
